EARTH PLUG REMOVER

Marshall J. Kramer, Creve Coeur, Mo.
(11301 Trieste, St. Louis, Mo. 63141)

Filed Jan. 21, 1974, Ser. No. 435,122

Term of patent 14 years

Int. Cl. D8—01

U.S. Cl. D8—7

FIG. 1

FIG. 2

FIG. 3

FIG. 4

FIG. 5

FIG. 1 is a perspective view of an earth plug remover, showing my new design;

FIG. 2 is a front elevational view thereof;

FIG. 3 is a top plan view thereof;

FIG. 4 is a bottom plan view thereof; and

FIG. 5 is a fragmentary, cross sectional view taken on line 5—5 of FIG. 2.

I claim:

The ornamental design for an earth plug remover, substantially as shown.
